Primary Examiner — Darlington Ly(74) *Attorney, Agent, or Firm* — Renner, Otto, Boisselle & Sklar, LLP(57) **CLAIM**

The ornamental design for a frame part of electric scooter, as shown and described.

DESCRIPTION

1. Frame part of electric scooter

1.1 is a top, rear, and left side perspective view of a frame part of electric scooter showing my new design.

1.2 is a left side elevation view thereof, the right side elevation view being a mirror image thereof;

1.3 is a front elevation view thereof;

1.4 is a rear elevation view thereof;

1.5 is a top plan view thereof; and,

1.6 is a bottom plan view thereof.
